(57) **CLAIM**

The ornamental design for a trivet, as shown and described.

DESCRIPTION

FIG. 1 is a front perspective view of the trivet showing my new design;

FIG. 2 is a top plan view thereof and it is the mirror image of a bottom plan view; and,

FIG. 3 is a front elevation view thereof and is identical to rear elevation, right elevation and left elevation views thereof.

The invention is a device on which hot or cold utensils may be placed to prevent damage to the supporting surface.
